UNITED STATES PATENT OFFICE.

FRED C. HOWE, OF PASADENA, CALIFORNIA.

SPOTLIGHT.

Application filed February 2, 1925. Serial No. 6,246.

This invention relates to spot lights, and it relates particularly to a spot light construction which is adapted for use wherever it is desired to have a spot light capable of 5 projecting light rays in a wide range of directions.

It is an object of my invention to provide a spot light of this character which is adapted for securing to a plate, such as 10 a windshield. Spot lights are used extensively on automobiles. My invention is adapted for securing to the windshield of an automobile. The lamp proper of my construction is situated to the outside or in 15 front of the windshield, and the operating handles are situated behind or inside the windshield.

It is another object of my invention to provide a spot light of this character which 20 will require only a small hole in a windshield to permit the extension therethrough. There are at present on the market lamps of this character which have a ball and socket arrangement located at the place at which 25 the body of the lamp extends through the windshield. This arrangement requires a very large hole in the windshield.

It is another object of my invention to provide a spot light of the character mentioned in which the lamp thereof will have 30 an extremely large lighting radius. I provide my invention in the form of a rotatable body having a swingable member pivoted thereto, this swingable member carrying the lamp of the spot light. A handle is provided for rotating the body of the 35 spot light, and a handle is provided for swinging the swingable member relative to the body. This arrangement permits the 40 lamp to be swung into any forward angular position with regard to the axis of the body of the spot light.

It is a further object of my invention to provide a spot light of this character which 45 is easily operated. My invention provides operating means in the form of a pair of adjacently situated handles, one handle being for the purpose of rotating the body, and the other handle being for the purpose 50 of swinging the swingable member. It is very convenient to swing one of the handles relative to the other or to swing both of the handles, thus swinging the lamp into any desired direction.

55 Other objects and advantages of my invention will be made evident hereinafter.

Referring to the drawing which is for illustrative purposes only,

Fig. 1 is a side elevational view of a spot light embodying the features of my 60 invention, the spot light being shown as supported by the windshield of a vehicle.

Fig. 2 is a partially sectioned view taken substantially on the line 2—2 of Fig. 1.

Fig. 3 is a section taken on the line 3—3 65 of Fig. 2.

Fig. 4 is a section taken on the line 4—4 of Fig. 2.

The form of my invention shown in the drawing comprises a body 11 having a tubular projection 12 which extends through an opening 13 in a plate such as a windshield 14. A friction plate 15 is formed on the body 11, which friction plate 15 carries a resilient pad 16. The resilient pad 16 is disposed in an annular recess 17 formed in the friction plate 15 and is arranged to engage with an outer face 18 of the windshield 14. On the portion of the tubular projection 12 which extends inside the windshield 14 is placed a sleeve 21, this sleeve 21 having an opening 22 therethrough through which the tubular projection 12 extends. The friction plate 23 is formed on the sleeve 21, this friction plate having 75 an annular recess 24 which carries a resilient pad 25. The resilient pad 25 is arranged to engage a face 26 of the windshield 14. 80

A body rotating handle 27 is secured on the extreme end of the tubular member 12 90 by means of a screw 28 which extends through a hub 29 of the handle 27 and threads into the tubular projection 12.

The opening 22 through the sleeve 21 is enlarged at 30 and the hub 29 of the body 95 rotating handle 27 extends into the enlargement 30, thus closing the end thereof. Compressed between a face 32 and the end 33 of the hub 29 is a coil spring 34. The coil spring 34 retains the pads 16 and 25 resiliently in engagement with the faces 18 and 100 26 of the windshield 14. The head 35 of the screw 28 extends into a slot 36 formed in the end of the sleeve 21. By rotating the handle 27, the body 11 is rotated and the sleeve 21 is also rotated due to engagement between the head 35 and the slot 36 of the sleeve 21. 105

At the extreme outer end of the body 11 110 which is located forwardly with respect to the windshield 14 is formed a clevis 38 having parallel extending arms 39. Outer

faces 41 of legs 42 of a swingable or pivot member 43 engage inner faces 44 of the arms 39 of the clevis 38. A shim 45 is provided between one of the legs 42 and one of the arms 39 to retain proper frictional engagement therebetween. The swingable member 43 is pivoted to the legs 39 by means of pivot screws 46 which thread through openings 47 in the legs 42. Heads 10 49 of the screws 46 are cylindrical and rest in cylindrical bearing openings 50 provided in the legs 39. A threaded boss 51 of the swingable member 43 threads into a fixture 52 of a lamp 53.

15 A bevel gear 55 is secured to one of the legs 42 of the swingable member 43 by means of one of the screws 46 and by means of rivets 56. A pinion gear 57 is arranged between the legs 39 of the clevis 38 and meshes 20 with the bevel gear 55. The pinion gear 57 is pinned to a shaft 59 which extends axially through an opening 60 formed in the body 11. The shaft 59 extends entirely through the body 11 and has secured thereto 25 at the extreme end thereof a swinging handle 61. The handle 61 is secured to the end of the shaft 59 by means of a pin 62 which extends through a hub 63 of the handle 61 and through the shaft 59, and by a screw 30 64 which threads into the end of the shaft 59. The handle 61 as clearly shown in the drawings is located adjacent to the handle 27. When the handle 61 is rotated, the pinion gear 57 is rotated by means of the shaft 59. This causes the bevel gear 55 to 35 rotate and the swingable member 43 to be swung relative to the body 11.

The spot light of my invention is very easy to operate, and has an extremely large range 40 of directions of projection. The lamp 53 may be directed into any direction by swinging the member 43 and by rotating the body 11. As an example, the handle 61 is rotated and the lamp 53 is swung into a position indicated by the dotted lines 68 of Fig. 2. In 45 other words, the lamp 53 is swung from a center line 66 so that the center line thereof extends as indicated at 67 in Fig. 2. By rotating the handle 27, the swingable member 43 and the lamp are rotated. This 50 swings the lamp through a circular path and moves the lamp into any circular position around the axis 66. The lamp 53 may be 55 swung at any angle with respect to the center line 66 of the body 11 within 90° in this modification of the invention, and by rotation of the body 11, the lamp may be swung circularly into any position of a complete circle. This arrangement gives a range of 60 direction including a half sphere, and the

lamp 53 may be extended in any direction within the limits of this half sphere.

As is obvious from Fig. 2, it will be seen that the opening in the windshield 14 is very small, it being necessary only to accommodate the tubular projection 12. The spot light arrangement is very simple in its construction and is very easy to install.

I claim as my invention:

1. In a device of the class described, the combination of: a rotatable body, said body comprising a clevis formed at one end of said body and a tubular projection formed at the opposite end of said body, said tubular projection being adapted for extension 70 through an orifice in a plate; a sleeve disposed on the end of said projection projecting through said plate; a spring for resiliently holding said body and said sleeve in contact with the faces of said plate; a handle secured to said tubular projection whereby said body is rotated; a lamp supporting member pivotally secured to said clevis; a gear secured to said lamp supporting member; a pinion gear meshing with said gear whereby said gear is rotated, thus pivotally swinging said lamp supporting member relatively to said body; a shaft extending through said body, said shaft supporting said pinion gear; and a handle secured on the end of said shaft whereby said shaft is rotated, thus rotating said pinion gear.

2. A combination as defined in claim 1 in which said body and said sleeve each have a friction plate adapted to frictionally engage the faces of said plate.

3. A combination as in claim 1 in which said spring is arranged inside said sleeve around said tubular projection.

4. In a device of the class described, the combination of: a rotatable body having a tubular projection adapted to extend through an opening in a plate, and a friction plate arranged to contact said plate; a lamp supporting member pivoted to said body, and supporting a lamp; a sleeve disposed on said tubular projection and having a friction plate adapted to engage said plate; a handle for rotating said body; a spring compressed between said handle and said sleeve for resiliently holding said friction plates in contact with said plate, said spring resting in a space within said sleeve and engaging said sleeve and said handle; and means for pivoting said lamp supporting member relatively to said body.

In testimony whereof, I have hereunto set my hand at Los Angeles, California, this 9th day of January, 1925.

FRED C. HOWE.
